[57] CLAIM

The ornamental design for a water-tight container, as shown and described.

DESCRIPTION

FIG. 1 is a front perspective view of a water-tight container of our design;

FIG. 2 is a left side elevational view thereof;

FIG. 3 is a right side elevational view thereof;

FIG. 4 is a rear elevational view thereof;

FIG. 5 is a front elevational view thereof;

FIG. 6 is a top plan view thereof;

FIG. 7 is a bottom plan view thereof;

FIG. 8 is a front perspective view of another embodiment of our design; and,

FIG. 9 is a top plan view of the embodiment of FIG. 8.

The unshown views of the water-tight container disclosed in FIGS. 8 and 9 are the identical to the corresponding FIGS. 3, 4 and 7 views, but scaled appropriately.
